UNITED STATES PATENT OFFICE.

ARTHUR S. KNIGHT, OF NEWARK, NEW JERSEY, ASSIGNOR TO WESTINGHOUSE LAMP COMPANY, A CORPORATION OF PENNSYLVANIA.

INCANDESCENT LAMP.

1,116,595.

Specification of Letters Patent. Patented Nov. 10, 1914.

Application filed November 3, 1909. Serial No. 526,045.

To all whom it may concern:

Be it known that I, ARTHUR S. KNIGHT, a subject of the King of Great Britain, and a resident of Newark, in the county of Essex and State of New Jersey, have invented a new and useful Improvement in Incandescent Lamps, of which the following is a specification.

My invention relates to electric incandescent lamps, and it has for its object to provide a lamp in which the filament is symmetrically disposed with respect to the arbor and in which the arbor is so constructed as to be capable of withstanding a very high degree of heat without injury.

The single figure of the accompanying drawing is a side view of a lamp embodying the present invention.

Extending centrally through the bulb of the lamp and from one end to near its other end, is an arbor comprising a tubular stem portion 1 and a wire portion 2 that is mounted in a short extension 3 of the stem portion 1 and is preferably composed of nickel. Extending through the tubular stem portion of the arbor are terminal leads 4 and 5 that project laterally therefrom into the bulb of the lamp and are provided with looped inner extremities. Projecting laterally from the extension 3, and upon the opposite side of the arbor from the terminal leads is a resilient filament support 6 having a hooked extremity. Upon the free end of the wire portion 2 of the arbor is a glass tip 7 in which are mounted resilient filament supports 8 that extend for a short distance in the direction of the arbor and are then bent to project laterally from the axis thereof, the extremities being hooked. The said supports are also displaced around the axis of the arbor approximately 90° from the supports 6. A reversely bent filament 9, having hooked extremities that engage the looped ends of the terminal leads, extends between the said leads and is supported at its intermediate bight portions by means of links 10 that are, in turn, supported by the hooked extremities of the filament supports. Filaments of large cross-section are preferably shaped upon a former before application to their supports, so that when applied to the supports, they are maintained thereby under a suitable degree of tension to prevent

their sagging. The portion of the arbor of the lamp that is in such close proximity to the filament as to be heated thereby to a high degree, being constructed of wire, is not detrimentally affected by the heat. The arrangement of the filament and its supports with respect to the arbor is also such that an exceptionally good distribution of light occurs.

I claim as my invention:

1. An incandescent lamp comprising an arbor, a pair of terminal leads and a filament support projecting laterally from substantially opposite sides of the arbor near one end thereof, two filament supports projecting from opposite sides of the arbor at its other end and displaced around the axis of the arbor approximately 90° from the aforesaid filament support, and a substantially W-shaped filament extending between the terminal leads and carried thereby and by the said filament support. 75

2. An incandescent lamp comprising an arbor, a pair of terminal leads and a resilient filament support projecting laterally from substantially opposite sides of the arbor near one end thereof, two resilient filament supports projecting from opposite sides of the arbor at its other end and displaced around the axis of the arbor approximately 90° from the aforesaid filament support, and a substantially W-shaped filament 80 extending between the terminal leads and carried thereby and by the said filament supports. 85

3. An incandescent lamp comprising a substantially W-shaped filament the middle 90 and outer legs of which respectively occupy different planes that are angularly disposed with respect to each other.

4. An incandescent lamp comprising an arbor and a substantially W-shaped filament the middle legs of which are located upon the opposite side of the arbor from the outer or end legs thereof. 95

In testimony whereof, I have hereunto subscribed my name this 18th day of October, 1909.

ARTHUR S. KNIGHT.
